[57] CLAIM

The ornamental design for a exterior surface of a vehicle console, as shown and described.

DESCRIPTION

FIG. 1 is a front view of the exterior surface of a vehicle console with the lid in closed position, showing our new design;

FIG. 2 is a top plan view thereof, with the lid shown in open position;

FIG. 3 is a reduced front left perspective view thereof with the lid shown in open position, it being understood that the right side is a mirror image of the side shown; and,

FIG. 4 is a reduced front left perspective view thereof with the lid shown in closed position, it being understood that the right side is a mirror image of the side shown.
